UNITED STATES PATENT OFFICE.

GEORGE DAVIDSON AND WILLIAM W. CLAY, OF PARIS, ONTARIO, CANADA.

NEEDLE-CYLINDER FOR CIRCULAR-KNITTING MACHINES.

SPECIFICATION forming part of Letters Patent No. 352,399, dated November 9, 1886.

Application filed April 22, 1886. Serial No. 199,808. (No model.)

To all whom it may concern:

Be it known that we, GEORGE DAVIDSON, of the town of Paris, in the county of Brant, in the Province of Ontario, Canada, knitter, and 5 WILLIAM WILLIAMS CLAY, of the same place, manufacturer, have jointly invented certain new and useful Improvements in Needle-Cylinders for Circular - Knitting Machines, of which the following is a specification.

10 The object of the invention is to so arrange the needles in the needle-ring that each needle may be independently removed and replaced without disturbing any of the other needles in the needle-ring, and which ring is so connected 15 to the cylinder-arms that it may be readily removed and replaced by another needle-ring of a different diameter; and it consists, essentially, of a peculiarly-formed needle-carrier made in sections and having vertical grooves 20 cut in it to receive the needles, which have peculiarly - shaped shanks to fit into the said grooves, each plate being independently secured by a screw-bolt passing through the holding-plate, the needle-carrier, and screwed into 25 the needle-ring, which is detachably connected to the cylinder-arms, substantially in the manner as hereinafter more particularly explained.

Figure 1 is a perspective view, partially in section, of our improved device. Fig. 2 is a perspective independent view of the cylinder-arms and hub. Fig. 3 is an enlarged detail of a portion of the needle-carrier in which one needle is set. Fig. 4 is a detail of the needle.

In the drawings, A represents the four cylinder-arms, which are connected to the machine in the ordinary manner. Each of these arms has a slot, a, through which the screws B pass in order to enter the screwed holes in the flange of the needle-ring C.

35 40 By forming the slots a in the arms A it will be noticed that we can readily remove the needle-ring C and replace it with one of a different diameter; but as the screws B might not secure the ring C with sufficient rigidity, we place on the arms A a series of holding-pins, b, which enter corresponding holes made in the flange of the needle-ring C.

D is a needle-carrier, made, as indicated in Fig. 1, in sections, so that it can be readily removed and replaced when necessary. On the 45 50 inside of the needle-carrier D we form a projection or wide rib, d, to fit into a recess made

to receive it and formed in the ring C. On the outside of the needle-carrier D a series of vertical grooves, e, are made, to receive the shanks f of the needles, each of which shanks is made a snug fit of its respective groove, all of which are exactly the same size and shape, so that the needles are interchangeable. The end of the shank f is bent, as at g, so that when the shank is fitted into its groove e its bent end g will fit into a notch, h, made in the bottom side of a shoulder, i, made in the outside of the carrier, d, at the base of the slots. In fitting each needle into its groove the end g is first slipped 65 into its notch h. The shank f is then pressed into its notch, and the beveled shoulder, j, formed on the shank, butts against the top edge of the needle-carrier D, and the needle is thus rigidly held from moving in either vertical direction. 7c When the needles are placed in position, the holding-plates E are put on separately, and are secured in position by the screw-bolts F, which pass through holes in the plate E and carrier D, and are screwed into the needle - ring C. 75 When thus screwed in, the plates E hold the needles rigidly in position.

From this description it will be seen that by merely removing one of the plates E any single needle can be removed and replaced by another without disturbing any of the other needles in the needle-ring.

It will be noticed on reference to Fig. 1 that a groove is cut on the inner face of the holding-plates E, to receive the shoulder i when the 80 said plate is screwed into position.

What we claim as our invention is—

1. The cylinder-arms A, having the slots a made in them, in combination with the detachable needle-ring C, secured in position by the 85 screws B and holding-pins b, substantially as and for the purpose specified.

2. The cylinder-arms A, needles, needle-carrier D, formed with wide rib d and grooves e, to receive the shanks f of said needles, and 95 the needle-ring C, secured to the cylinder-arms, and having a groove formed on its outside to receive the rib d, combined with the detachable holding-plates E and means for holding said plates in position, substantially as and for 100 the purpose specified.

3. The ring c, the needles, the needle-carrier D, made in sections and having vertical grooves e formed in it, and a projecting shoulder or rib,

; made near its base, in combination with the holding-plates E, secured by the screw-bolts F, and having grooves cut on their inner side to receive the shoulder i, substantially as and for the purpose specified.

4. A knitting-machine needle having a shank, f, with a bent end, g, and a beveled shoulder, j, in combination with a needle-carrier, D, having a slot, e, to receive the shank

f, and a notch, h, to receive the end g, substantially as and for the purpose specified.

Paris, April 16, 1886.

GEORGE DAVIDSON.
W. W. CLAY.
